CLAIM

The ornamental design for an beauty fill light, as shown and described.

DESCRIPTION

FIG. 1 is a front, top and right side perspective view of a beauty fill light, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged detail view of area 8 in FIG. 1; and,

FIG. 9 is an enlarged detail view of area 9 in FIG. 3.

The broken lines in the figures are for the purpose of illustrating portions of the beauty fill light, which form no part of the claimed design. The dash dot lines are demarcating enlarged areas and form no part of the claimed design.
